CLAIM

The ornamental design for a tire as shown and described.

DESCRIPTION

The patent or application file contains at least one drawing executed in color. Copies of this patent or patent application publication with color drawing(s) will be provided by the Office upon request and payment of the necessary fee.

1. Tire

1.1 : Front

1.2 : Left

1.3 : Perspective

1.4 : Enlarged

Fig. 1.1 is a front view of a tire; the design is repeated around the circumference of the tire; Fig. 1.2 is a left side view thereof, the right side view being identical thereof; Fig. 1.3 is a perspective view thereof; the design is repeated around the circumference of the tire; Fig. 1.4 is an enlarged view of part A; The red box with the indication "A" shown in fig. 1.1 is included to indicate the enlarged part of the tire shown in fig. 1.4.
